UNITED STATES PATENT OFFICE

151,049

DESIGN FOR A COMBINED BISCUIT, DOUGH-NUT, AND PASTRY CUTTER

Earl J. Kilgore, Evarts, Ky.

Application April 19, 1946, Serial No. 128,790

Term of patent 3½ years

(Cl. D44—29)

To all whom it may concern:

Be it known that I, Earl J. Kilgore, a citizen of the United States of America, residing at Evarts, in the county of Harlan and State of Kentucky, have invented a new, original, and ornamental Design for Combined Biscuit, Doughnut, and Pastry Cutter, of which the following is a specification, reference being had to the accompanying drawing, forming part thereof.

Figure 1 is a bottom plan view of a combined biscuit, doughnut and pastry cutter showing my new design.

Figure 2 is a side view thereof.

Figure 3 is a top plan view.

I claim:

The ornamental design for a combined biscuit, doughnut, and pastry cutter, as shown.

EARL J. KILGORE.
